INTERNAL-COMBUSTION ENGINE

Charles G. Curtis, New York, N. Y.

Application November 26, 1943, Serial No. 511,772

4 Claims. (Cl. 123—74)

This invention applies to the "uniflow" type of two-cycle Diesel or gas engine which is provided with inlet ports at the bottom of the stroke and an exhaust valve or valves at the top of the stroke.

The object I have in view is to provide a simple mechanism for furnishing the necessary scavenging air without adding materially to the moving parts so as to dispense with a separate scavenging blower or compressor, and to provide an effective and simple means and construction for supplying the scavenging air to the cylinder without the provision of any header or headers.

In the drawings, Figure 1 is a sectional view of the engine frame and one of the cylinders taken at right angles to the crankshaft.

Fig. 2 is a vertical sectional view through the center of the cylinder taken at right angles to the view in Fig. 1.

Fig. 3 is a diagram of valve timing for going ahead.

Fig. 4 is a diagram of valve timing for going astern.

Fig. 5 is a modification of the valve timing in Fig. 4.

Fig. 6 is a modified form of my engine in which in place of automatic valves controlling the scavenging air, I provide valve mechanism driven from a lay-crankshaft.

Fig. 7 is a cross section of the engine, Fig. 1, through the chamber 14.

In Fig. 1 numeral 10 represents the cylinder; 11 the inlet ports, and 12 exhaust poppet valve or valves operated in the usual way by a cam 13. Extending over the length of the engine or over several cylinders I provide a longitudinal chamber or compartment 14 into which the cylinders 10 project, so that this compartment feeds directly into the scavenging ports 11. The lower wall of this chamber or compartment consists of a diaphragm or plate 15 through which the piston rod 16 projects; this piston rod serving to transmit the power from the short piston 17 to the auxiliary or crosshead piston 18.

I make the crosshead in the shape of a round piston which fits closely into the guiding (auxiliary) cylinder 19 which is made a part of, or attached to the engine frame, this piston thus acting not only as a crosshead to take the side thrust of the connecting rod, but as a scavenging air compressor. I provide spaces or passages 20 on each side of the engine which lead into the automatic valves 21 and 22. Valves 21 connect with chambers 23 and valves 22 lead into the

scavenging air chamber 14. When the scavenging piston moves downward it produces a suction in the passages 20 which causes the valves 21 to lift off their seats and air is drawn in through these valves from the air chambers 23. When the piston 18 moves upward it compresses the air above it causing the automatic valves 21 to close instantly, and when the pressure has risen to a point a little above the scavenging pressure in the chamber 14 the valves 22 lift off their seats and the air is forced into the chamber 14. By making the piston 18 slightly larger—about 20 per cent larger in diameter than the main piston 17 a displacement by the piston 18 is obtained about 44 per cent greater than the displacement of the power piston 17, and allowing for volumetric efficiency I provide a scavenging air ratio of about 125 per cent, which is more than ample to obtain a high scavenging efficiency.

I find that it is not necessary, under most conditions, to provide a packing in the diaphragm 15 where it surrounds the piston rod. A clearance of sufficient amount can be provided between the diaphragm and piston to avoid contact, and the quantity of air that will be lost by passing downward from the chamber 14 into the passage 20 will be practically negligible, and has the advantage of blowing back oil which may work up on the piston rod 16. Several sets of valves can be provided at each side in line with each other, so as to provide ample valve capacity and these valves can readily be reached by covers 25.

I slope the diaphragm 15 from the center downward so that the sludge will run down to the rim of the diaphragm from where it can be drawn off periodically through the tube or drain passage 26. The vertical divisions 27 in the frame are carried upward to the top of the chamber 14 so as to give the necessary strength and to support the diaphragm 15. As the piston 17 moves downward it forces the air into the chamber 14 and tends to raise the pressure in that chamber to some extent. When this piston goes up it tends to produce some suction in chamber 14. In order to equalize the pressure in the different sections of the chamber under each cylinder so as to maintain a substantially constant scavenging pressure in chamber 14, I provide large openings or passages 27' (Fig. 7) through which the air can flow from one division of the chamber to the next division. Meanwhile the scavenging air is being intermittently forced into the chamber 14 through the valves. In this way I am enabled to dispense entirely with an independent scavenging header and the engine will be free from pro-

jecting portions and can be made smooth on the surface, so that it can readily be kept clean.

In order to avoid taking the strain of the gas pressure on the cylinder head through the bridges between the inlet ports I bolt the cylinder to the compartment 14 making the joint above the level of the ports, the cylinder being held down by a flange 30 with the bolts arranged on the four corners and of sufficient strength to take the entire gas strain on the cylinder head. These bolts or studs 31, reaching down through the chamber 14, four bolts to each cylinder, are screwed into the frame 23 or carried downward to the base, according to the ordinary practice. By making the joint between the cylinder and the engine frame at a point above the scavenging ports there will be no gas pressure at this joint. By this arrangement I am enabled to take off the cylinder and head to get at the piston rings or the valves, and thus avoid the necessity of breaking the gas-tight joint at the top of the cylinder. Instead of having the bolts or studs 31 reach down to the base, they may be threaded into the framework at the level of the automatic inlet valves.

In Fig. 6, I have shown another form of scavenging air valve which may be preferable in a high speed engine where the automatic valves are not so well adapted to high speed. In this case, I employ for each cylinder a piston valve 33, reciprocated by a crank 34 on a crankshaft on which I also mount the injection oil pumps. I time this piston valve so that when the piston is going up the ports 35 are open and the air is forced up into the chamber 24 through connecting passage 36. As the crosshead piston approaches the top the valve shifts rapidly so as to close the passage through 36 and open the ports 37 and also ports 35, so as to connect the passage 20 with the chamber 29. As the crosshead piston descends it sucks air in from the chamber 29 through the ports 37 and through the ports 35 into the clearance space 20. By making the piston of sufficient size and the ports of sufficient length, I am enabled to introduce the air into the clearance 20 on one stroke and to deliver air into the passage 26 on the next stroke with very little loss of pressure, and hence good efficiency.

What is claimed is:

1. In a uniflow internal combustion engine comprising a plurality of combustion cylinders and pistons and inlet ports in the combustion cylinders at the bottom-of-the-stroke position, a plurality of auxiliary cylinders and pistons, the latter connected by piston rods with the first named pistons and acting as crossheads; a chamber around and common to the plurality of combustion cylinders and with which each of said combustion cylinders may communicate through said inlet ports when the latter are uncovered by the respective pistons, a diaphragm separat-

ing said chamber from the auxiliary cylinders, valve mechanism constructed and operating to admit air to the respective auxiliary cylinders when the respective auxiliary pistons move in one direction and to admit to said common chamber compressed air for feeding said inlet ports when the auxiliary pistons move in the opposite direction.

2. In a uniflow internal combustion engine comprising a plurality of combustion cylinders and pistons and inlet ports in the combustion cylinders at the bottom-of-the-stroke position, a plurality of auxiliary cylinders and pistons, the latter connected by piston rods with the first named pistons and acting as crossheads; a chamber around and common to the plurality of combustion cylinders and with which each of the said combustion cylinders may communicate through said inlet ports when the latter are uncovered by the respective pistons, a diaphragm separating said chamber from the auxiliary cylinders, piston valve mechanism constructed and operating to admit air to the respective auxiliary cylinders when the respective auxiliary pistons move in one direction and to admit to said common chamber compressed air for feeding said inlet ports when the auxiliary pistons move in the opposite direction.

3. In a uniflow internal combustion engine comprising a plurality of combustion cylinders and pistons and inlet ports in the combustion cylinders at the bottom-of-the-stroke position, a plurality of auxiliary cylinders and pistons, the latter connected by piston rods with the first named pistons and acting as crossheads; a chamber around and common to the plurality of combustion cylinders and with which each of said combustion cylinders may communicate through said inlet ports when the latter are uncovered by the respective pistons, a diaphragm separating said chamber from the auxiliary cylinders, valve mechanism constructed and operating to admit air to the respective auxiliary cylinders when the respective auxiliary pistons move in one direction and to admit to said common chamber compressed air for feeding said inlet ports when the auxiliary pistons move in the opposite direction, said common chamber having bracing partitions with openings therein through which air may flow to all parts of said common chamber.

4. In a uniflow internal combustion engine according to claim 1, further characterized by said diaphragm having an opening through which said piston rod passes which is of slightly greater diameter than the diameter of the piston rod, so a small amount of air may escape downwardly and blow back oil which may work upwardly on the piston rod.
